UNITED STATES PATENT OFFICE.

PAUL G. PATER, OF HAMILTON, OHIO, ASSIGNOR TO THE LONG & ALLSTATTER COMPANY, OF HAMILTON, OHIO.

PUNCHING-MACHINE.

1,277,469.

Specification of Letters Patent. Patented Sept. 3, 1918.

Application filed February 8, 1918. Serial No. 215,946.

To all whom it may concern:

Be it known that I, PAUL G. PATER, a citizen of the United States, residing at Hamilton, Butler county, Ohio, have invented certain new and useful Improvements in Punching-Machines, of which the following is a specification.

This invention aims at mechanism designed to facilitate the accuracy of punching operations and will be readily understood from the following description taken in connection with the accompanying drawings in which:—

Figure 1 is a side elevation of a punching machine fitted with an exemplification of my invention;

Fig. 2 a vertical section of portions thereof in the plane of line *a* of Figs. 3 and 4;

Fig. 3 a front elevation of the punch and its near accessories; and

Fig. 4 a horizontal section in the plane of offset lines *b* of Figs. 2 and 3.

In the drawings:—

1, indicates the body of the punching machine;

2, the vertically reciprocating ram thereof;

3, the cam-shaft for reciprocating the ram:

4, the punch:

5, the die:

6, the stripper:

7, a faceplate on the body, forming the front guide-surface of the ram:

8, the plate to be punched:

9, prick-punch marks in the plate at the centers of location of the holes to be punched in the plate:

10, a teat on the end of the punch, all of the parts thus far referred to being constructed substantially as usual, except as hereinafter stated, and subject to any of the usual modifications:

11, a recess near the base of the ram:

12, the punch-stock carrying the punch at its lower end and held in the base of the ram:

13, a collar on the upper end of the stock, the height of the collar and the height of the recess 11 being relatively such that the stock may have some degree of free reciprocating motion in the ram:

14, a block secured in the base of the ram, a semi-circular recess in the rear face of this block and a semi-circular recess in the front portion of the base of the ram to the

rear of the block forming a bore in which the punch-stock fits and slides:

14^a, a stud projecting downward from the block:

15, a fork projecting from the punch-stock 60 and freely straddling the stud:

16, an adjusting nut on the stud, below the fork:

17, the bolts for securing the block to the base of the ram, this block and bolt arrangement being designed to furnish a convenience in assembling the punch-stock and ram: 65

18, a pair of jaws pivoted to the top of the block and projecting into the recess in 70 the ram and adapted for such opening and closing motion as will adapt them to be free from the collar 13 or to swing in under the shoulder formed by the collar:

19, the pivots on which the jaws oscillate: 75

20, a stem having its rear end coupled to the two jaws:

21, a T-shaped head on the inner end of this stem and engaging in slots in the front ends of the jaws: 80

22, a lever disposed at the front of the face-plate and block and having its heel mounted on a pivot carried by the block:

22^a, a helical spring surrounding stud 20, 85 its rear end engaging against the lever, stud 20 passing freely through the lever:

23, an adjusting nut on the stem, to serve in adjusting the tension of spring 22^a:

24, an inclined cam carried by the face-plate above the jaws: 90

25, a roller carried by the free end of the lever and adapted to engage cam 24 and swing the lever outwardly as the ram descends:

26, a spring stud carried by the block and projecting freely outward through the lever and adapted to urge the lever rearwardly: 95

27, a setscrew passing through the lever and adapted to engage the block:

28, the pivot on which the lever swings: 100 and

29, the pivots connecting the jaws with stem 20, these pivots being inward of the pivots 19 on which the jaws are mounted.

Giving consideration to Fig. 2, the ram 105 is in its uppermost position; the punch is resting on the plate to be punched; the teat is in one of the punch marks of the plate; the plate may be shifted about as desired, the coned teat causing the punch 110

to rise, the teat dropping into a selected prick-punch mark; the ram starts down; the punch remains stationary supported by the plate; the roof of recess 11 eventually 5 engages the top of the punch-stock; the ram continues its descent and the punch is forced through the plate; the descent of the ram has brought the top of the open jaws below the level of the shoulder at the foot of collar 13; the roller has engaged cam 24 and swung 10 the lever outwardly and closed the jaws under the collar; the ram rises; the punch-stock and punch are pulled upward; the punch is withdrawn from the plate, which is held down by the stripper; the lever swings 15 inwardly; the jaws release from under the collar; the punch-stock and punch may descend by gravity; in the absence of the plate their descent would be limited by the engagement of the fork with nut 16; the parts 20 are in condition for the shifting of the plate for a new punching operation.

If, instead of the plate illustrated, a thinner plate be put under the punch then the 25 teat would not reach the plate and the desired feeling, on the part of the operator, for the punch mark, could not be accomplished. By adjusting nut 16 on its stud, the 30 normal idle floating position of the punch, that is to say, in the absence of a plate, may be adjusted to suit any thickness of plate within the capacity of the device. When the 35 ram is up and a plate present, the punch is a floating punch, being supported by the plate when the plate is present, and being supported at the proper vertical height by the nut 16 when the plate is absent. The 40 plate being absent, and the floating punch being supported by nut 16, the plate may be inserted edgewise between the punch and die, the cone of the teat elevating the punch a trifle and permitting the point of the teat to ride on the plate.

From a study of Fig. 2, it will be apprehended that the jaw arrangement constitutes a let-go device, of a known class, to drop the punch to floating position after it has been raised sufficiently high for the stripping; that when the plate is present nut 16 is without office; that when the plate is absent, then the punch could drop too low for the re-insertion of the plate if the nut were not present; that if all plates were of the same thickness the nut would constitute a supporting 55 device and no adjustment of it would be needed; and that by reason of its being a threaded agent it becomes an adjustable supporting device to prevent the punch from dropping so low as to prevent the convenient 60 insertion of a new plate, whatever the thickness of the plate adjusted for, within the capacity of the adjustment.

The program of events which have been given, or the result of the program rather, 65 would be brought about if the lever or stud

20 were operated by hand, but the cam and roller arrangement makes the operation of the jaws automatic. The employment of block 14 provides a peculiarly convenient means for forming an openable bore to receive the punch-stock in case the collar is integral with the punch-stock, thus preventing the assembling of the punch-stock and ram by an endwise motion of the punch-stock, and at the same time the block carries the lever and jaws and stud 14^a, which provides a very convenient assemblage of parts. 70

Spring 26 has merely the office of urging the lever inwardly, while the office of spring 22^a is to render elastic the connection between the jaws and the lever so as to provide for inaccuracies of construction and movement. For instance, if this connection were not elastic it might be that the jaws closed completely upon the punch-stock while the 75 lever was still straining outwardly upon stud 20.

If it be desired to temporarily abandon the floating scheme it may be done by adjusting set-screw 27 inwardly against the 80 block until the lever is forced outwardly and held permanently in a position corresponding with the closed position of the jaws under the collar of the punch-stock, under which conditions the punch will partake of 85 substantially the full rising and falling motion of the ram. The floating scheme may be restored to activity by merely backing out the setscrew 27 to the idle position illustrated. When the invention is realized in a 90 vertically reciprocating punch, as illustrated, the gravity of the punch-stock serves 95 as the agent for pressing the idle punch to the surface of the plate being punched, or pressing the fork to the nut 16 when the 100 plate is absent.

I claim:—

1. A punching machine comprising, a reciprocating ram, a punch-stock having a limited reciprocating motion in the ram, and an adjustable supporting device disposed between the punch-stock and the ram and serving to adjustably limit the protrusion of the punch-stock from the ram when there is no plate present for the punch to float upon, 110 combined substantially as set forth.

2. A punching machine comprising, a reciprocating ram, a punch-stock having a limited reciprocating motion in the ram, an adjustable supporting device disposed between the punch-stock and the ram and serving to adjustably limit the protrusion of the punch-stock from the ram, a downwardly presenting shoulder formed upon the punch-stock, pivoted jaws carried by the ram and 120 adapted to open and close upon the punch-stock below said shoulder, and means for moving the jaws to open and closed position, 125 combined substantially as set forth.

3. A punching machine comprising, a re- 130

- 5 ciprocating ram, a punch-stock having a limited reciprocating motion in the ram, an adjustable supporting device disposed between the punch-stock and the ram and serving to adjustably limit the protrusion of the punch-stock from the ram, a downwardly presenting shoulder formed upon the punch-stock, pivoted jaws carried by the ram and adapted to open and close upon the punch-stock below said shoulder, a pivoted lever carried by the ram, and an elastic connection between the lever and the jaws to open and close the jaws as the lever is oscillated, combined substantially as set forth.

10 4. A punching machine comprising, a reciprocating ram, a punch-stock having a limited reciprocating motion in the ram, an adjustable supporting device disposed between the punch-stock and the ram and serving to adjustably limit the protrusion of the punch-stock from the ram, a downwardly presenting shoulder formed upon the punch-stock, pivoted jaws carried by the ram and adapted to open and close upon the punch-stock below said shoulder, a pivoted lever carried by the ram, an elastic connection between the lever and the jaws to open and close the jaws as the lever is oscillated, combined substantially as set forth.

15 5. A punching machine comprising, a reciprocating ram, a punch-stock having a limited reciprocating motion in the ram, an adjustable supporting device disposed between the punch-stock and the ram and serving to adjustably limit the protrusion of the punch-stock from the ram, a downwardly presenting shoulder formed upon the punch-stock, pivoted jaws carried by the ram and adapted to open and close upon the punch-stock below said shoulder, a pivoted lever carried by the ram, an elastic connection between the lever and the jaws to open and close the jaws as the lever is oscillated, and means for locking the lever in position corresponding with the closed position of the jaws, combined substantially as set forth.

20 6. A punching machine comprising, a reciprocating ram, a punch-stock having a limited reciprocating motion in the ram, an adjustable supporting device disposed between the punch-stock and the ram and serving to adjustably limit the protrusion of the punch-stock from the ram, a downwardly presenting shoulder formed upon the punch-stock, pivoted jaws carried by the ram and adapted to open and close upon the punch-stock below said shoulder, a pivoted lever carried by the ram, an elastic connection between the lever and the jaws to open and close the jaws as the lever is oscillated, and a fixed cam carried by the frame-work of the machine and adapted to vibrate the lever and close the jaws as the ram moves downwardly, combined substantially as set forth.

25 7. A punching machine comprising, a reciprocating ram, a punch-stock having a limited reciprocating motion in the ram, a stud carried by the ram, an adjusting nut on the stud, and a fork carried by the punch-stock and adapted to engage said nut to limit the protrusion of the punch-stock from the ram, combined substantially as set forth.

30 8. A punching machine comprising, a reciprocating ram having a recess in its base, a block secured against the lower portion of the ram and adapted in conjunction with the base of the ram to furnish a vertical bore for a punch-stock, a punch-stock fitted to slide vertically in such bore, and a collar on the upper end of the punch-stock to be engaged by the roof of the recess in the ram in the course of the descending motion of the ram, combined substantially as set forth.

35 9. A punching machine comprising, a reciprocating ram having a recess in its base, a block secured against the lower portion of the ram and adapted in conjunction with the base of the ram to furnish a bore for a punch-stock, a punch-stock fitted to slide in such bore, a collar on the upper end of the punch-stock to be engaged by the roof of the recess in the ram in the course of the descending motion of the ram, pivoted jaws mounted on the block and adapted to co-operate with the punch-stock, a lever pivoted to the block, and a connection between the jaws and lever to cause the vibration of the lever to open and close the jaws, combined substantially as set forth.

40 10. A punching machine comprising, a reciprocating ram, a punch-stock having a limited reciprocating motion in the ram, an adjustable supporting device disposed between the punch-stock and the ram and serving to adjustably limit the protrusion of the punch-stock from the ram, a downwardly presenting shoulder formed upon the punch-stock, pivoted jaws carried by the ram and adapted to open and close the punch-stock below said shoulder, a pivoted lever carried by the ram, an elastic connection between the lever and the jaws to open and close the jaws as the lever is oscillated, and a normally idle setscrew carried by the lever and adapted to be adjusted to position to lock the lever to position corresponding with the closed position of the jaws, combined substantially as set forth.

45 11. A punching machine comprising, a die, a punch to co-operate therewith, a reciprocating ram to push the punch through a plate and into the die and to withdraw

50 12. A punching machine comprising, a reciprocating ram, a punch-stock having a limited reciprocating motion in the ram, an adjustable supporting device disposed between the punch-stock and the ram and serving to adjustably limit the protrusion of the punch-stock from the ram, a downwardly presenting shoulder formed upon the punch-stock, pivoted jaws carried by the ram and adapted to open and close the punch-stock below said shoulder, a pivoted lever carried by the ram, an elastic connection between the lever and the jaws to open and close the jaws as the lever is oscillated, and a normally idle setscrew carried by the lever and adapted to be adjusted to position to lock the lever to position corresponding with the closed position of the jaws, combined substantially as set forth.

55 13. A punching machine comprising, a reciprocating ram, a punch-stock having a limited reciprocating motion in the ram, an adjustable supporting device disposed between the punch-stock and the ram and serving to adjustably limit the protrusion of the punch-stock from the ram, a downwardly presenting shoulder formed upon the punch-stock, pivoted jaws carried by the ram and adapted to open and close the punch-stock below said shoulder, a pivoted lever carried by the ram, an elastic connection between the lever and the jaws to open and close the jaws as the lever is oscillated, and a normally idle setscrew carried by the lever and adapted to be adjusted to position to lock the lever to position corresponding with the closed position of the jaws, combined substantially as set forth.

60 14. A punching machine comprising, a reciprocating ram, a punch-stock having a limited reciprocating motion in the ram, an adjustable supporting device disposed between the punch-stock and the ram and serving to adjustably limit the protrusion of the punch-stock from the ram, a downwardly presenting shoulder formed upon the punch-stock, pivoted jaws carried by the ram and adapted to open and close the punch-stock below said shoulder, a pivoted lever carried by the ram, an elastic connection between the lever and the jaws to open and close the jaws as the lever is oscillated, and a normally idle setscrew carried by the lever and adapted to be adjusted to position to lock the lever to position corresponding with the closed position of the jaws, combined substantially as set forth.

65 15. A punching machine comprising, a reciprocating ram, a punch-stock having a limited reciprocating motion in the ram, an adjustable supporting device disposed between the punch-stock and the ram and serving to adjustably limit the protrusion of the punch-stock from the ram, a downwardly presenting shoulder formed upon the punch-stock, pivoted jaws carried by the ram and adapted to open and close the punch-stock below said shoulder, a pivoted lever carried by the ram, an elastic connection between the lever and the jaws to open and close the jaws as the lever is oscillated, and a normally idle setscrew carried by the lever and adapted to be adjusted to position to lock the lever to position corresponding with the closed position of the jaws, combined substantially as set forth.

it therefrom, a stripper to limit the rising of the plate from the die as the punch is withdrawing from the plate, a let-go device connecting the punch with the ram to cause the punch to rise with the ram and then be released to descend and float upon the plate, and a supporting device carried by the ram and serving to limit the descent of the punch after release in the absence of a plate, where-
10 by the released punch may become arrested at a distance from the die sufficient for the insertion of a plate between them, combined substantially as set forth.

12. A punching machine comprising, a
15 die, a punch to coöperate therewith, a reciprocating ram to push the punch through a plate and into the die and to withdraw it therefrom, a stripper to limit the rising of

the plate from the die as the punch is withdrawing from the plate, a let-go device connecting the punch with the ram to cause the punch to rise with the ram and then be released to descend and float upon the plate, and an adjustable supporting device carried by the ram and serving to limit the descent of the punch after release in the absence of a plate, whereby the released punch may become arrested at an adjusted distance from the die sufficient for the insertion of a plate between them, combined substantially as set forth.
